ABSTRACT OF THE DISCLOSURE

A variable frequency microwave generator coupled to a waveguide containing a Stark septum and terminating in a crystal detector for obtaining a spectroscopic analysis of gas contained within the waveguide. High and low frequency modulation of the signal passing through the waveguide identifies with improved accuracy the resonant absorption peaks of the gas.

This invention relates in general to microwave spectroscopy and more particularly to apparatus for high sensitivity microwave spectroscopy.

In microwave spectroscopy the molecular composition of a gas is studied by determining the microwave frequencies at which absorption peaks occur. The basic apparatus which has been used for such study consists of a variable frequency microwave generator, a microwave crystal detector and a waveguide coupling the two together with the waveguide containing the gas to be analyzed. The absorption peak is then determined by scanning the frequency of the microwave generator across the range of interest and measuring the variations in microwave power at the detector. Inasmuch as a typical value for the reduction of the absorption peak is around 10^{-5} for each centimeter of waveguide length, extreme sensitivity of measurement is required. Thus, in a waveguide of 100 centimeters length the reduction would amount to only around 10^{-8} , or 0.1%. The problem is compounded when the purpose of the study is to determine parts per million of one gas within another gas, since a 10 part per million concentration, for example, would typically result in an absorption of only around 10^{-8} , or one millionth of 1%, in a one-meter waveguide.

Since the measurement under discussion is that of the comparison of microwave power received when an absorption peak is present to that of the power received without any absorption peak, then any variation in this ambient power level constitutes a noise background for the measurement. There are several sources of such noise. One source is the noise from the crystal detector itself. This noise generally decreases with increasing frequency and is generally referred to as "1/f noise." Another source of noise is variation in power level at the microwave generator ("oscillator noise"), while still a third is the variation in transmission efficiency of the microwave guide as a function of frequency.

In the past there have been a number of approaches to the problem of reducing the noise for microwave spectroscopy measurements. One such approach consisted of frequency modulating the microwave source and employing a tuned circuit such as a tuned amplifier on the output of the detector so that the system responded only to frequencies at and about the modulating frequency. Under these circumstances, the reduction of 1/f noise and noise due to power fluctuations of the generator led to an increase in signal to noise ratio. In a more refined system, the output signal from the amplifier was rectified (in some cases, in synchronism with the modulation frequency),

2

and the resulting direct current voltage level, which then constituted the output signal from the device, was averaged over a relatively long time period (e.g., 1 second). In order to determine the location of absorption peaks, the frequency of the microwave generator was scanned slowly across the range of interest and the output from the rectifier was displayed on a chart recorder to provide a visual waveform. The principal difficulty with this system lay in the fact that the frequency modulation employed resulted in the generation of numerous spurious signals due to the variation of transmission efficiency of the system with frequency.

In another approach, a thin electrically conductive plate was mounted centrally within the waveguide and extended longitudinally along the waveguide. This plate was insulated from the waveguide and sufficient voltage (typically, around 1000 volts) was applied between this electrode and the waveguide to create an electrostatic field of sufficient strength to produce the Stark effect. In the Stark effect, the presence of a high electrostatic field causes a splitting of the absorption peak. For example, if the absorption peak were at a frequency f_0 , then the presence of a sufficient electrostatic field would create a pair of absorption peaks of reduced amplitude, one at a lower frequency than f_0 and one at a higher frequency, and the original peak at f_0 would have disappeared almost completely. (Because of this Stark effect, the central electrode used in this configuration of waveguide has become known as a Stark septum.) In this mode of operation the voltage creating an electrostatic field was applied at some relatively high frequency between the Stark septum and the wall of the waveguide, and the output circuit from the crystal detector was tuned to this frequency. This output was then rectified as described above. The direct current amplitude at the output thus represented the difference between microwave absorption with and without the electrostatic field. Accordingly, the signal amplitude did not include, at least primarily, variations due to variations in transmission efficiency of the waveguide. A difficulty that still remained with this system, however, although of second order, arose from the fact that the Stark modulation was likely in many cases to produce a small modulation of the transmission characteristics of the waveguide system. Additionally, in certain cases where broadband electrical tuning was required, the microwave generator usually employed was a backward wave oscillator. When this generator is used in conjunction with a high frequency Stark field, radiation from the Stark field is likely to frequency modulate its output. This modulation introduces variations in the microwave signal received at the detector due to variations of transmission characteristics with frequency. To obviate such difficulties, which were particularly pronounced at low signal levels, the frequency of the microwave generator was slowly varied over an appropriate range so as to permit visual recognition of the waveform. This range normally included the frequencies at which the displaced peaks would occur as well as the original frequency of the absorption peak so as to provide for a more unique criterion of signal recognition.

Another problem which was common to both the frequency modulation and Stark modulation systems arose when it was attempted to use exceedingly long time constants on the output of the rectifier in an attempt to increase the signal-to-noise ratio. This was impractical because of the fact that the rectified output would be likely to drift slowly with time so that in many cases this slow drift would become indistinguishable from the waveform which was to be generated by a slow frequency scan over the absorption peak. In a more refined system this difficulty was obviated to some degree by conversion of the DC level at the output of the rectifier to a pulse repeti-

tion rate. As the DC level would vary the pulse repetition rate would vary. The pulse output was then applied to a channel of a multichannel digital storage system. The microwave frequency was then varied relatively rapidly, i.e., before the ambient level at the output of the rectifier would have a chance to change significantly. In synchronism with the variation in microwave frequency, subsequent channels of the multichannel storage system would be addressed. This procedure was then repeated many times over so as to provide a long time constant averaging of the waveform. The difficulty associated with this system was that a considerable portion of the measurement time was spent in making measurements at frequencies where the signal-to-noise ratio was very low.

It is therefore a primary object of the present invention to provide apparatus for microwave spectroscopy for accurate and efficient determination of absorption peaks.

It is another object of this invention to provide apparatus for microwave spectroscopy in which noise in the output signal is significantly suppressed.

It is still another object of this invention to provide apparatus for microwave spectroscopy in which the generation of spurious signals by Stark modulation are suppressed.

It is yet another object of this invention to provide apparatus for microwave spectroscopy wherein provision is made for the use of long time constants without the necessity of making measurements at points other than at the absorption peak.

Broadly speaking, in the spectroscopy system described herein, the spectrometer is formed with a variable frequency microwave generator coupled to a waveguide containing a Stark septum and terminating in a crystal detector. An alternating current signal at a fixed, relatively high, frequency is coupled to the spectrometer to vary the microwave power received by the crystal detector in accordance with the microwave absorption characteristic of the particular gas within the waveguide at the frequencies of operation of the microwave generator. As will appear in more detail below, this variation may be accomplished in either of two ways, one, by using the AC signal to frequency modulate the microwave generator or, alternatively, by using the AC signal to vary the voltage applied between the Stark septum and the wall of the waveguide. A tuned amplifier at the output of the crystal detector is tuned to this relatively high frequency and the phase-sensitive detector which is used to rectify the output from the amplifier is synchronized with this AC signal. Since the amplifier passes only frequencies in a relatively narrow bandwidth around the high frequency, there is considerable reduction of the $1/f$ noise and oscillator noise.

In addition to this high frequency variation, a second much lower frequency component is provided in the output signal. This component is generated either by a switch operated at predetermined intervals, such as one second intervals, or by a relatively slow AC source. In the case where the high frequency variation is introduced by frequency modulation of the microwave generator, the low frequency variation is introduced by varying the voltage applied to the Stark septum. In this instance, the output from the high frequency phase detector is a voltage level varying at the low frequency. Alternate halves of this resulting voltage waveform are indicative of signal plus noise, while the other halves represent noise lone. However, both halves include the ambient D.C. level of the rectifying circuit. The alternate outputs may be digitalized and accumulated separately in a pair of scalers to determine the ratio of the signal to noise, or alternatively, a second phase detector synchronized with the low frequency signal source may be coupled to the output of the first phase detector. The DC output from this second phase detector is then directly proportional to the difference between the modulated signal with and without the Stark effect. Since this arrangement permits a direct de-

termination of the microwave power level with and without a Stark field, the microwave generator may be maintained fixed at the frequency of the absorption peak for a gas of interest, without the necessity of sweeping the frequency to determine the waveform.

In the second case, when the high frequency variation is introduced by application of an alternating Stark field, the low frequency component is provided by low frequency reversal of the phase of the Stark field with respect to the source of the high frequency modulation signal. This change of phase results in a change of polarity of the D.C. output signal. Since only the Stark field has changed phase, then, in the resultant low frequency waveform, the ambient level at the output of the detector first adds, then subtracts from the signals and is therefore cancelled out. This output may be treated in the same fashion as that for the first case.

Other objects and advantages will become apparent from the following detailed description when taken in conjunction with the accompanying drawings in which:

FIG. 1 is an illustration in block diagram form of a spectroscopy apparatus constructed in accordance with the principals of this invention;

FIG. 2 is a plan view of a waveguide element suitable for use in the practice of this invention;

FIG. 3 is a cross-sectional view taken along the line 3—3 of FIG. 2;

FIG. 4 is a cross-sectional view taken along the line 4—4 of FIG. 3;

FIG. 5 is an illustration in block diagram form of a second embodiment of a spectroscopy apparatus constructed in accordance with the principals of this invention;

FIG. 6 is an illustration partially in block diagram and partially in schematic form of a circuit for producing an electrostatic field within a waveguide, which circuit is suitable for use in the practice of this invention;

FIG. 6A is an illustration in schematic form of a switching arrangement which may be substituted for the low frequency AC generator shown in FIG. 6;

FIG. 7 is an illustration in block diagram form of output circuitry suitable for use in a spectroscopy apparatus as illustrated in either FIG. 1 or FIG. 5;

FIG. 8 is an illustration in block diagram form of another embodiment of an output circuit suitable for use in the spectroscopy apparatus as illustrated in either FIG. 1 or FIG. 5; and

FIG. 9 is a graphical illustration of waveforms helpful to an understanding of this invention.

With reference now to FIG. 1, a microwave generator 11 is coupled to one end of a waveguide 12, the other end of which is coupled to a crystal detector 13. The microwave generator may be a typical commercially available generator operating in the K band or K_a band and would most usually be a backward wave oscillator such as a Varian Associates Model VA-163. The waveguide 12 is constructed generally as an elongated cylinder of perhaps two meters length having a rectangular cross section with the cross section dimensions typically being 0.4 inch by 0.9 inch. Further details of the waveguide construction are illustrated in FIGS. 2, 3 and 4. The waveguide includes at either end a flange portion 17 and the openings at each end are sealed off by mica windows 18 so that the overall waveguide may be considered as gas tight. As above mentioned, the purpose of this spectroscopy apparatus is the analysis of the microwave absorption characteristic of a gas. The waveguide 12 then serves as the test chamber in which microwaves are transmitted through the gas to be analyzed. This waveguide is evacuated through port 27, and after evacuation the test gas is supplied to the waveguide 12 through the same port 27. The waveguide is formed, as illustrated in FIGS. 3 and 4, with a Stark septum 25 bisecting it longitudinally. The Stark septum is formed as a thin conducting plate supported within the waveguide on insulators 26, which typi-

cally would be formed of Teflon rails. The Stark septum at either end is narrowed down to a point in order to minimize end effects. An electrical connector 14 provides for electrical contact to the Stark septum insulated from the waveguide 12. The detector 13 coupled to the output side of the waveguide is a conventional microwave is a conventional microwave crystal detector such as a IN26C.

Referring again to FIG. 1, the output from the detector 13 is shown connected to a tuned amplifier 14, the output of which is in turn connected to an output circuit 15. The microwave generator 11 has applied to it a high frequency AC modulating signal from AC source 21 and this same signal is provided to the output circuit 15. The tuned amplifier 14 is tuned to this same frequency; the value of the frequency is selected to be sufficiently high so that the 1/f noise is very low. A typical value is 100 kc./sec. An amplifier bandwidth of about 10 kc./sec. for this frequency is satisfactory. A field circuit 22 for providing a Stark field is coupled through electrical connector 14a to the Stark septum 25 and this field circuit 22 also provides a signal to output circuit 15. The field circuit 22 provides for the application of an electrostatic field between the Stark septum 25 and the wall of the waveguide 12. This field is arranged to be of sufficient magnitude, typically 1000 volts, to produce the Stark effect on the absorption peak of a gas which is to be analyzed. In its simplest form, the field circuit 22 for this apparatus would consist of a square wave generator capacitatively coupled to the Stark septum and operated at a suitable frequency, that is, one which is relatively low compared to that of the high frequency AC source 21, and yet one in which the time period is short compared to the traversal time of the generator 11 over a frequency absorption line. In one mode of operation this field circuit 22 might operate at a frequency of 100 cycles per second. As above indicated, the amplitude of the waveform applied to the Stark septum 25 would be in the order of volts and a signal at this same frequency, but of lesser amplitude, is supplied to the output circuit 15.

The exact configuration of the output circuit 15 will depend upon the mode of operation of the overall system. Thus, the system may be operated either by maintaining the microwave generator 11 at a frequency corresponding to an absorption peak frequency for the gas to be analyzed or alternatively this frequency may be swept slowly over a range of interest in order to provide an actual measurement of the waveform of the absorption peak.

In the latter case, that is, where the microwave generator 11 is to be swept slowly over a range of frequency, output circuit 15 is generally of the form illustrated in FIG. 8. As shown in FIG. 8, the output from the tuned amplifier 14 is rectified by being applied to a phase sensitive detector 61 which is synchronized by the signal from the high frequency AC source 21. The output then from this phase sensitive detector 61 is in essence a rectified 100 kc./sec. signal. This output from the phase sensitive detector 61 is now applied to a second phase sensitive detector 62, which is synchronized by the 100 cycle per second signal from the field circuit 22. Hence the output from this second detector is the rectified 100 cycle per second component of the output signal from the phase sensitive detector 61.

The operation of the microwave spectrometer illustrated in FIG. 1 is as follows. The microwave generator 11 provides microwaves to the waveguide 12, which microwaves are modulated at the high frequency of the AC source 21, with the amplitude of this modulation being made approximately equal to the line width of the absorption peak. When the frequency at which the microwave generator 11 is operated is equal to the absorption frequency of the gas to be tested, this modulation then causes the microwave power transmitted to vary periodically from a value at one peak equal to the ambient microwave level

to a value equal to the maximum absorption level at the other peak, with this variation occurring at twice the modulation frequency. It should be noted that when the frequency of operation of the microwave generator 11 is, for example, 1/4 of a line width removed from the peak absorption frequency, this same variation in general occurs. However, in this instance a frequency equal to the modulation frequency itself becomes predominant.

In the specific descriptions of the apparatus given above, as well as in those which will appear below, the amplifier is described as tuned to the modulation frequency and the phase sensitive detector is synchronized by this same frequency. It is evident that those elements may instead be tuned to the second or higher harmonics of the fundamental frequency.

In addition to this high frequency variation there is a low frequency variation in transmitted microwave power. This low frequency variation results from varying the Stark field which produces a variation from the peak absorption level to the ambient level, with this second variation occurring at a lower frequency, in this instance 100 cycles per second. The output signal from the tuned amplifier 14 then contains a 100 kc./sec. component due to the frequency modulation of the microwave generator 11 and a low frequency modulation component due to the variation of the Stark field. The output from the phase sensitive detector 61 (FIG. 8) is, in essence a 100 cycle per second wave of amplitude equal to the difference between the microwave transmission with and without the Stark effect. By applying this signal to the second phase sensitive detector 62, which is synchronized by a signal from the field circuit 22, a rectified output signal is produced in which the direct current level is now proportional to the difference between the microwave power transmitted with and without the Stark effect. By scanning the frequency of the microwave generator 11 over the frequency range of interest, the output signal appearing on output 24 as a function of time will have the waveform of the absorption peaks of the gases contained within the waveguide 12.

The microwave spectrometer illustrated in FIG. 1 can also be operated in the mode where the frequency of the microwave generator 11 remains fixed at a frequency corresponding to the absorption frequency of a gas which is to be quantitatively determined. In this instance the field circuit 22 would generally not be a conventional square wave generator but would rather be a 1000 volt supply which is alternately applied and removed from the Stark septum 25 by means of a motor controlled switch. In this instance the switch would operate at a value of, typically, one switching action per second, and the Stark field would therefore be applied for one second, removed for one second, and so forth. In this instance the output circuit 15 would not correspond to the configuration illustrated in FIG. 8. A suitable form of output circuit for this mode is shown in FIG. 7. In this circuit the signal from the tuned amplifier 14 is applied to a phase-sensitive detector 45 which is synchronized by the signal from the high frequency AC source 21. The output from phase sensitive detector 45 is then applied to a voltage controlled oscillator 51. The voltage controlled oscillator 51 generates output pulses at a repetition rate proportional to the DC voltage level at its input. The output from the voltage controlled oscillator 51 is coupled through a switch 54 to either one of these two scalers, and is actuated back and forth by means of a cam 53 operated by a motor 52. This actuating cam 53 also controls the switching of the Stark field switch 55. In this mode of operation the high frequency source again modulates the frequency of the microwave power applied to the waveguide 12; however, the variation in the Stark field occurs much more slowly than the previous typical value of 100 c./s. Once again, the output from phase-sensitive detector 45 is a signal which varies at the rate of alternation of the Stark field and the amplitude of this slowly varying component is

equal to the difference in microwave absorption with and without the Stark field. The output from the voltage controlled oscillator 51 is then a signal which alternates between two repetition rates, one representing the microwave power transmitted with a Stark field and the other representing the microwave power transmitted without the Stark field. By synchronizing the action of the switch 54 with the action of the Stark field switch 55, one scaler, e.g., 48, accumulates pulses representing the microwave transmission with the Stark field while the other scaler accumulates pulses representing the microwave transmission without the Stark field. The apparatus may be run for a considerable period of time and the accumulated difference between the counts on scaler 48 and scaler 49 represents this difference between signal and noise over a long integration period.

If the voltage controlled oscillator 51 is made to have a logarithmic response, i.e., wherein the logarithm of the output frequency varies as the input voltage level, then it should be noted that the logarithm of the ratio of the counts accumulated on scaler 48 to the counts accumulated on scaler 49 is now proportional to the difference in levels and hence proportional to the magnitude of the microwave absorption peak. One advantage of such an arrangement is that timing errors may be corrected by reversing the phase of the slow Stark variation with respect to the cam operated counter switch 54. By then taking the geometric mean of the two ratios which are obtained, any systematic error in the timing device is cancelled.

Referring now to FIG. 5, a second and preferred embodiment of the microwave spectroscopy system is shown. In this system both the high frequency and the low frequency variation in the microwave transmission are accomplished within the Stark field circuit and there is no frequency modulation of the microwave generator itself. A microwave generator 31 is coupled to a waveguide 32 which in turn is coupled to a crystal detector 33. The output of the crystal detector 33 is connected through a tuned amplifier 34 to an output circuit 35. A field circuit 43 is coupled to waveguide 32 and provides also two independent signals to output circuit 35. The microwave generator 31, waveguide 32, crystal detector 33, and tuned amplifier 34 are all identical to the components used in the system illustrated in FIG. 1. The output 35 will again depend upon the exact mode of operation of the system but will have the general form illustrated in either FIG. 7 of FIG. 8. The field circuit 43 in this instance differs significantly from the Stark field circuit used in the system of FIG. 1.

In FIG. 6 there is shown a configuration of the field circuit 43 which produces a Stark field and is suitable for operating the microwave spectroscopy system of FIG. 5 in the sweeping mode, that is, where the frequency of microwave generator 31 is swept over the range of interest. In the field circuit illustrated in FIG. 6 a square wave generator 41 has one terminal capacitatively coupled through capacitor C to the Stark septum 25 while the other terminal is connected to the wall of waveguide 12. Square wave generator 41 would be a generator operating typically at a frequency of approximately 100 kilocycles/sec. and providing sufficient output voltage to create the Stark effect within the waveguide. This voltage would have a nominal value of 1000 volts peak to peak. Also included in this field circuit is a low frequency AC generator 47 which provides a voltage output of approximately 1000 volts peak to peak but at a much lower frequency, for example, 100 cycles per second. One terminal 49a of this low frequency generator is connected through resistor R to the Stark septum while the other terminal 50 is connected directly to the wall of the waveguide 12. The time constant formed by the combination of the resistor R and the capacitor C may be any convenient value provided that it is somewhat less than the reciprocal of the frequency of the low frequency AC generator 47, while at the same time the resistance R is generally chosen to be

large in comparison to the driving impedance of square wave generator 41.

In operation, a 1000 volt signal is being applied between the Stark septum and the wall of the waveguide 12 at a repetition rate of approximately 100 kilocycles/sec. At the same time the 1000 volt signal is being applied from the low frequency AC generator 47 at a 100 cycle per second rate across the same two points. The effect of the low frequency signal is to cause a phase shift in the Stark effect, that is to change the phase at which the absorption peak is split.

Referring to FIG. 9, curve a represents the 100 kc./sec. waveform when the polarity of the 100 c./s. waveform is positive. Under these conditions the voltage on the Stark septum varies from zero to a positive value with respect to the waveguide wall. The Stark effect occurs when this voltage is at +V. Curve b of FIG. 9 shows the 100 kc./sec. waveform when the polarity of the 100 c./s. waveform is negative. The voltage on the Stark septum now varies from zero to a negative value. Since the Stark effect depends only on the presence of the electrostatic field and is essentially independent of polarity, it now occurs when the septum voltage is at -V. As indicated by the diagonal dotted line, the effect of the 100 cycle waveform is then to shift the phase of the 100 kc. waveform at which the Stark effect occurs. If the output circuit is as shown in FIG. 8, and the first phase sensitive detector 61 is synchronized with a signal from the square wave generator 41, then its output will be a rectified 100 kc./sec. wave. The change in phase which occurs at the low frequency rate of 100 c.p.s. will cause the polarity of this rectified signal to vary at this low frequency rate. Since the phase difference occurs only with respect to the Stark field, then any ambient levels produced by 100 kc./sec. interference, or as for example, by slight frequency modulation of the microwave oscillator, fail to produce variation on the rectified signal at the given low frequency rate. Ordinarily, any ambient level at the output of the phase-sensitive detector fails to produce such a low frequency variation except that which is due to the Stark effect itself.

The output of the first phase-sensitive detector is coupled to the second phase sensitive detector 62, which is synchronized with the signal from the low frequency AC generator 47. The output from this second phase detector is then the rectified 100 c.p.s. signal, and the DC value of this signal is thus proportional to the signal amplitude of the difference between transmission with and without the Stark field.

When the spectroscopy system illustrated in FIG. 5 is operated in the second mode, that is with the frequency of the microwave generator 31 maintained at a selected value corresponding circuit 35 generally takes the form illustrated in FIG. 7. In addition, the field circuit 43 is somewhat modified from the configuration shown in FIG. 6. In this mode the field circuit 43 does not include a low frequency AC generator 47 but rather a switching arrangement is connected between terminals 49 and 50. This switching arrangement may conveniently take the form shown in FIG. 6A in which a double pole, double throw switch 55 and a voltage source 57 are interconnected to form a circuit which provides a voltage between terminals 49a and 50 with the polarity of this voltage being reversed by changing the position of the arm of the switch 55. In this mode, the operation is substantially the same as that for the sweeping mode in that the reversal of polarity of the voltage applied between terminals 49a and 50 changes the phase of the variation of the Stark effect with respect to the high frequency produced by square wave generator 41. The output circuit illustrated in FIG. 7 again provides a suitable form of output circuit for this second mode of operation. In this instance the cam actuator 53 would be used to effect the switching change in the double pole, double throw switch 55. The synchronizing signal for the phase detector 45 is derived, as before, from the square wave generator 41. A typical value

for the frequency with which the switch is actuated is approximately one change per second.

The invention has been described in terms of two specific embodiments of spectrometer systems employing the Stark effect. It is apparent that, while specific components have been shown for these illustrations, a number of equivalent components may also be employed. Thus, in the non-sweeping mode counters have been used as the integrating circuits at the output. Many other forms of integrating circuits are suitable such as capacitor tanks and other memory devices which are suitable for relatively long time integration. Similarly, a variety of components and arrangements may be utilized to perform the switching functions and to generate the voltage and perform the readout of the DC levels. The invention has also been described in terms of systems which employ the Stark effect. A spectrometer system incorporating these same principles may also be constructed using the Zeeman effect rather than the Stark effect. In the Zeeman effect the splitting of the absorption peak is produced by generating a suitable magnetic, rather than electrostatic, field. In the Zeeman effect spectrometer the systems illustrated in FIG. 1 or in FIG. 5 may be used. In this case however the waveguide would be formed of aluminum, or a glass tube with focussing electrodes and the magnetic field would be created with conventional means such as inductive loops. The field circuit 22, in the system illustrated in FIG. 1 would now be a low frequency current source supplying current to produce the magnetic field. Similarly, in the system of FIG. 5, the field circuit 43 would be formed of high and low frequency current source coupled to an inductive coil. It may be noted that in all cases the frequency absorption characteristic of the gas is varied at the low frequency to produce the low frequency change in microwave power received at the detector.

Having described the invention, various modifications and improvements will now occur to those skilled in the art and the invention disclosed herein should be considered as limited only by the spirit and scope of the appended claims.

What is claimed is:

1. Apparatus for measuring the microwave absorption characteristics of a gas comprising,
  - a microwave generator for generating microwaves at a selected frequency;
  - a waveguide coupled to said microwave generator, said waveguide being formed to constitute a chamber for containing gas to be measured;
  - a microwave detector coupled to said waveguide for measuring the microwave power transmitted along said waveguide and providing an electrical output indicative thereof;
  - a first means for producing a first variation with time in the microwave power received by said detector, the magnitude of said first variation being controlled by the microwave absorption characteristic of said gas at said selected frequency;
  - second means for producing a second variation with time in the microwave power received by said detector by changing the microwave absorption characteristic of said gas, said first means providing a time variation at a first frequency and said second means providing a time variation at a second frequency substantially lower than said first frequency;
  - an amplifier coupled to said microwave detector, said amplifier being tuned in a relatively narrow bandwidth around said first frequency; and
  - output means coupled to said amplifier for providing output signals indicative of the microwave absorption characteristics of said gas;
  - said first means comprising a source of alternating current voltage coupled to said microwave generator for frequency modulating said microwave generator at said first frequency; and
  - said second means comprising means for generating within said waveguide an electrostatic field which

varies at said second frequency from a minimum value to a maximum value where said maximum value is sufficient to significantly affect said absorption characteristics of said gas within said waveguide at said selected frequency.

5 2. Apparatus in accordance with claim 1 wherein said waveguide is formed as an elongated chamber for transmission of microwaves along the longitudinal axis thereof, and further including an electrode longitudinally bisecting said waveguide, said second means being coupled between said waveguide and said bisecting electrode for producing an electrostatic field between said bisecting electrode and said waveguide.

10 3. Apparatus in accordance with claim 1 wherein said second means includes a second source of alternating current voltage operating at said second frequency and wherein said output means comprises a first phase sensitive detector coupled to said amplifier output, said first phase sensitive detector being operated synchronously with said source of AC voltage within said first means, and a second phase sensitive detector coupled to the output of said first phase sensitive detector, said second phase sensitive detector being operated synchronously with said source of AC voltage within said second means.

15 4. Apparatus in accordance with claim 1 wherein said second means includes a second source of alternating current voltage operating at said second frequency and wherein said output means comprises a first phase sensitive detector coupled to said amplifier output, said first phase sensitive detector being operated synchronously with said source of AC voltage within said first means, and a second phase sensitive detector coupled to the output of said first phase sensitive detector, said second phase sensitive detector being operated synchronously with said second source of AC voltage within said second means.

20 5. Apparatus in accordance with claim 1 wherein said second means includes a switch, said switch being repetitively operated at predetermined intervals for applying and removing said electrostatic field within said waveguide, said predetermined intervals being such that said field is applied and removed at said second frequency, and wherein said output means includes a rectifying means coupled to the output of said amplifier, said rectifying means being synchronously operated with said AC voltage source in said first means and wherein the output from said rectifying means is coupled to a first terminal when said switch is in one position and to a second terminal when said switch is in a second position.

25 6. Apparatus in accordance with claim 3 but including a voltage controlled oscillator of logarithmic characteristic coupled between said switch and said output from said phase sensitive detector whereby the output from said voltage controlled oscillator is coupled to a first terminal when said switch is in one position and to a second terminal when said switch is in a second position.

30 7. Apparatus for measuring the microwave absorption characteristics of a gas comprising:

- a microwave generator for generating microwaves at a selected frequency;
- a waveguide coupled to said microwave generator, said waveguide being formed to constitute a chamber for containing gas to be measured;
- a microwave detector coupled to said waveguide for measuring the microwave power transmitted along said waveguide and providing an electrical output indicative thereof;
- a first means for producing a first variation with time in the microwave power received by said detector, the magnitude of said first variation being controlled by the microwave absorption characteristic of said gas at said selected frequency;
- second means for producing a second variation with time in the microwave power received by said detector by changing the microwave absorption characteristic of said gas, said first means providing a time variation at a first frequency and said second means providing a time variation at a second frequency substantially lower than said first frequency;
- an amplifier coupled to said microwave detector, said amplifier being tuned in a relatively narrow bandwidth around said first frequency; and
- output means coupled to said amplifier for providing output signals indicative of the microwave absorption characteristics of said gas;
- said first means comprising a source of alternating current voltage coupled to said microwave generator for frequency modulating said microwave generator at said first frequency; and
- said second means comprising means for generating within said waveguide an electrostatic field which

variation at a first frequency and said second means providing a time variation at a second frequency substantially lower than said first frequency; an amplifier coupled to said microwave detector, said amplifier being tuned in a relatively narrow bandwidth around said first frequency; and output means coupled to said amplifier for providing output signals indicative of the microwave absorption characteristics of said gas;

5

said output means comprising a first detector means for rectifying that frequency component of said microwave detector electrical output corresponding to said first frequency and second detector means coupled to the output of said first detector means for rectifying that frequency component of the output from said first detector means corresponding to said second frequency.

10

7. Apparatus for measuring the microwave absorption characteristics of a gas comprising, a microwave generator for generating microwaves at a selected frequency formed as an elongated chamber for transmission of microwaves along the longitudinal axis thereof and further including an electrode longitudinally bisecting said waveguide; a waveguide coupled to said microwave generator, said waveguide being formed to constitute a chamber for containing gas to be measured; a microwave detector coupled to said waveguide for measuring the microwave power transmitted along said waveguide and providing an electrical output indicative thereof; a first means for producing a first variation with time in the microwave power received by said detector, the

magnitude of said first variation being controlled by the microwave absorption characteristic of said gas at said selected frequency;

second means for producing a second variation with time in the microwave power received by said detector by changing the microwave absorption characteristic of said gas, said first means providing a time variation at a first frequency and said second means providing a time variation at a second frequency substantially lower than said first frequency;

said first means comprising a source of alternating current voltage operating at said first frequency and means coupling said source of alternating current voltage between said waveguide and said bisecting electrode for varying the electrostatic field within said waveguide;

said second means comprising means for applying an alternating current voltage at said second frequency between said waveguide and said bisecting electrode; an amplifier coupled to said microwave detector, said amplifier being tuned in a relatively narrow bandwidth around said first frequency; and output means coupled to said amplifier for providing output signals indicative of the microwave absorption characteristics of said gas.
